(57) **CLAIM**

The ornamental design for display screen with graphical user interface, as shown and described.

DESCRIPTION

FIG. 1 is an image of a first embodiment of a display screen with graphical user interface showing our new design; and, FIG. 2 is an image of a second embodiment of a display screen with graphical user interface showing our new design.

The broken line showing of a mobile device illustrates the environment of the article and forms no part of the claimed design. The remaining broken lines, showing a display screen and portions of the graphical user interface, form no part of the claimed design.

1 Claim, 2 Drawing SheetsFIG. 1

FIG. 2
